ISAAC SNOW, OF LAWRENCE, MASSACHUSETTS, ASSIGNOR TO DRAPER CORPORATION,
OF HOPEDALE, MASSACHUSETTS, A CORPORATION OF MAINE.

FEELER MECHANISM FOR LOOMS.

1,387,205.

Specification of Letters Patent. Patented Aug. 9, 1921.

Application filed April 7, 1920. Serial No. 372,008.

To all whom it may concern:

Be it known that I, ISAAC SNOW, a citizen of the United States, and a resident of Lawrence, county of Essex, and State of Massachusetts, have invented an Improvement in Feeler Mechanisms for Looms, of which the following description, in connection with the accompanying drawings, is a specification, like characters on the drawings representing

10 like parts.

The present invention relates to feeler mechanisms for looms whereby the filling in the shuttle may be replenished prior to complete exhaustion thereof.

15 In that type of feeler mechanism wherein the feeler is moved longitudinally of the shuttle when the filling is substantially exhausted on a detecting beat, it has been common heretofore to effect such "side swipe" or lateral movement of the feeler either by means of the forward pressure thereagainst, on a detecting beat, or by means of mechanical devices which act upon the feeler. The present invention relates more particularly to feeler mechanisms of the first-mentioned type, that is, where the forward pressure upon the feeler effects side swipe or lateral movement thereof when the filling is substantially exhausted.

25 The feeler mechanism must be sensitive either to the presence or substantial absence of filling in the shuttle, and must be responsive to either condition, either to prevent or cause filling replenishment. Should the feeler mechanism call a change prior to the time when the filling in the shuttle has reached a substantial degree of exhaustion, the amount of waste incident to the change of the filling would be large and objectionable. On the other hand, should the feeler mechanism fail to call a change while there still remained sufficient filling in the shuttle to lay a full length of filling in the shed, defective cloth is liable to be produced.

30 One of the objects of the present invention, therefore, is to provide "side swipe" feeler mechanism wherein the feeler is given its side swipe or lateral movement longitudinally of the shuttle by forward pressure when the filling is substantially exhausted, and wherein, also, the parts are simple in construction and sensitive both to the pres-

ence and substantial absence of filling in the shuttle.

The present feeler mechanism embodies a 55 feeler which is yieldingly held rearwardly in its feeling position but is mounted to have a lateral movement imparted thereto upon the same being moved forward toward the front of the loom. The feeler is constructed to 60 bend intermediate its ends and to automatically resume its straightened position when the same is relieved from the bending force. This construction permits the engagement 65 of the rear end of the feeler with the filling 70 to hold this end from being moved laterally upon a detecting beat until substantial exhaustion of filling occurs, and causes this rear end to be moved laterally when the supply of filling in the shuttle is no longer 75 sufficient to hold the same against the lateral movement imparted to it by the force tending to straighten the feeler. As a result of this construction a satisfactory side swipe feeler consisting of very few parts is provided.

The features of the present invention and the novel combination of parts will be best understood from the following description and accompanying drawings of one good, 80 practical form of the invention.

In the drawings:

Figure 1 is a perspective view of the feeler side of the loom showing the feeler mechanism applied thereto, many of the loom 85 parts being omitted;

Fig. 2 is an enlarged plan view showing the action of the feeler mechanism when a working supply of filling is present on a detecting beat, part of the feeler mechanism 90 being shown in section; and

Fig. 3 is a view similar to that of Fig. 2 showing the action of the feeler mechanism when the filling is substantially exhausted.

The general loom construction and the replenishing mechanism whereby filling is replenished under call of the feeler mechanism, are not shown and described as they may be of usual and well known construction. The loom frame 1 has secured thereto 95 the brackets 2, one at each side of the loom frame, in which is mounted the transverse or rock shaft 3 of usual construction and from which rises the arm 4, to the upper

end portion of which at 5 is pivoted the latch 6. The forked rear end portion 7 of the latch 6 is adapted to be engaged at times by an operating member 8 which may be either 5 the cam follower or a part connected thereto.

The lay 9 is provided with the usual shuttle box 10 the front wall 11 of which is slotted or cut away, as indicated at 12, to register with an opening 13 in the side of the 10 shuttle, when the shuttle is boxed at the detecting side of the loom. The shuttle 14 contains the usual filling carrier 15. The loom frame 1 has extending therefrom the shipper stand 16 to a slotted arm 17 of which is adjustably secured the feeler carrier 18 by 15 means of the bolts 19 and upon the upper face of this carrier 18 the feeler stand 20 is preferably adjustably mounted by means of bolt or bolts 21. The adjustable bolts 19 and 21 enable the feeler to be adjusted so 20 that the same will properly enter the shuttle upon a detecting beat.

In the embodiment of the invention illustrated, the feeler is designated in its entirety 25 by the numeral 22, and this feeler is shown as consisting of a pair of sections 23 and 24 preferably secured together by a pivot pin 25. The section 24 extending toward the front of the loom is preferably rounded 30 throughout a portion of its length and the forward end of the same projects through an aperture formed in the upwardly directed end 26^a of the forwardly extending finger 26, and this finger may, if desired, be formed 35 integral with the feeler stand 20. The rearwardly extending section 23 of the feeler, in the embodiment shown, consists of a pair of longitudinally extending blades having a filling engaging strip 27 secured therebetween by means of rivets or the like 28. This strip 27 serves to retain the blades in spaced 40 relation to each other so that an end of the section 24 may be pivotally mounted between these blades by the pivot pin 25 above mentioned. In order that the sections 23 and 24 of the feeler 22 will be normally held in their extended position, as shown in Figs. 1 and 3, rather than in the bent position, shown in Fig. 2, a spring 29 is provided, an intermediate 45 portion of which may be looped about a pin 30 carried by the section 23 and one end of this spring reacts against a pin 31, while the opposite end 32 of this spring re-acts against the section 24. In order to limit the 50 extent to which one pivoted section may be swung by the spring 29 upon the other section, in the embodiment illustrated, the section 24 is shown as provided with a notch 33 adapted to engage a lug or stop 34 carried by the section 23. From the construction just 55 described it will be seen that the pivoted feeler 22 normally has its sections extending in a straight line with each other and that the spring 29 yieldingly resists a force tending 60 to bend the feeler.

In order to provide means for normally holding the feeler 22 in its rearward position, as shown in Fig. 1, a coil spring 35 may be provided, one end of which abuts against a shoulder on the section 24, while the opposite end reacts against the inner face of the upwardly extending end 26^a and the movement of the feeler in a rearward direction may be conveniently limited by a pin 36 extending through the forward end of the 70 feeler. A lateral movement is imparted to the feeler each time the same is moved toward the front of the loom, by means of a link 37 one end of which is pivotally secured to the feeler stand by a screw or the like 38, 80 and the opposite end of this link preferably extends in between the spaced blades of the feeler section 23 and is pivotally secured thereto by a pivot pin 39, the arrangement being such that as the feeler is forced toward 85 the front of the loom it is, at the same time, deflected laterally by the link 37. The rearwardly projecting end of the feeler is provided with filling engaging teeth 40 and as long as there is a substantial amount of filling 90 upon the bobbin the engagement of these teeth with the filling will prevent the rear end of the feeler 22 from being swung laterally, that is, longitudinally of the shuttle, notwithstanding the fact that a lateral movement is imparted to an intermediate portion of the feeler upon each detecting beat. The filling is able to hold the rear end of the feeler against lateral movement due to the fact that the feeler will bend intermediate 95 its ends against the tension of the spring 29, as clearly shown in Fig. 2, but when there is no longer a sufficient amount of filling present upon the bobbin to hold the rear end of the feeler against the force of the spring 29 100 tending to move the sections of the feeler to their extended position, this end of the feeler will move laterally to the position shown in Fig. 3. To provide means for preventing the feeler 22 from being lifted up off its 105 feeler stand an appreciable amount, there is provided the lug or finger 41 which may be formed integral with the feeler stand and the outer end of which extends upwardly and over a portion of the feeler, as clearly 110 shown in Fig. 1.

From the above description it will be apparent that as long as there is a substantial amount of filling present within the shuttle the rear end of the feeler will be prevented from moving laterally, but when substantial exhaustion occurs, this rear end will move laterally upon a detecting beat to the position shown in Fig. 3. In order to provide means for effecting replenishment 125 of filling by the lateral movement of the rear end of the feeler, in the embodiment shown, a feeler operated lever 42 is provided an intermediate portion of which is preferably pivotally mounted upon a portion 43 130

of the feeler stand by means of a screw or the like 44. One end of this lever is provided with an anti-friction roller 45 positioned adjacent the position occupied by the 5 rear end of the feeler when the same is held by the filling against lateral movement. The other end of this lever is preferably operatively connected by a connecting rod 46 to a latch supporting lever 47 and this last mentioned lever is preferably pivotally mounted 10 upon a stand 48 by means of a pivot pin 49. The portion of the lever 47 to which the rod 46 is connected preferably extends upwardly in the form of an arm, as at 50, and this 15 lever is provided with a second arm 51 which extends between the prongs of the forked lever 7 above mentioned. A third arm of this lever preferably abuts against the stop 52 carried upon the bracket 48. The operation 20 of the parts just described is such that whenever the feeler engaging end of the rocking lever 42 is forced to the right with respect to Fig. 1, by a lateral movement of the rear end of the feeler, this rocking of the 25 lever 42, through the connecting rod 46 will lift the latch 6 into the path of movement of the operating member 8 and will thereby effect replenishment of filling in a well known manner. The pivoted lever 42 is normally held in the position shown in Figs. 1 30 and 2 by the force of gravity due to the fact that one end of the latch 6 rests upon the laterally projecting arm 51 of the rocking lever 47.

35 **Claims—**

1. In a feeler mechanism for looms, the combination of a feeler jointed intermediate of its ends and supported to be engaged by a surface in the shuttle and pushed front- 40 wardly thereby on a detecting beat, means for yieldingly maintaining the sections of the jointed feeler extended substantially in alinement, teeth upon the feeler to engage the filling and hold the feeler from moving longitudinally of the shuttle, means for deflecting the intermediate portion of the feeler laterally as the feeler is pushed frontwardly by a surface in the shuttle when a substantial amount of filling is present and for mov- 45 ing the rear end of the feeler longitudinally of the shuttle when filling is substantially exhausted, and means operable upon movement of the feeler longitudinally of the shuttle to effect replenishment of filling.
- 55 2. In a feeler mechanism for looms, the combination of a feeler jointed intermediate of its ends and supported to be engaged by a surface in the shuttle and pushed front- 50 wardly thereby on a detecting beat, means for deflecting an intermediate portion of the feeler laterally when a working supply of filling is present in the shuttle as the feeler is pushed frontwardly on a detecting beat, and for imparting said deflecting movement 55 to the rear end of the feeler when the filling
- is substantially exhausted, teeth upon the feeler to engage the filling and hold the rear end of the feeler from moving longitudinally of the shuttle until substantial exhaustion of filling occurs, and means operable by the movement of the feeler longitudinally of the shuttle to effect replenishment of filling. 70
3. In a feeler mechanism for looms, the combination of a feeler mounted for movement longitudinally of the shuttle and to be pushed frontwardly by a surface in the shuttle on a detecting beat, said feeler being jointed intermediate of its ends to permit it to bend laterally, means for yieldingly resisting a force tending to bend the feeler, 75 means for deflecting the feeler laterally as it is pushed frontwardly on a detecting beat, teeth to engage the filling and hold the rear end of the feeler from moving longitudinally of the shuttle until substantial exhaustion of filling occurs, and means operable by the movement of the rear end of the feeler longitudinally of the shuttle to effect replenishment of filling. 80
4. In a feeler mechanism for looms, the combination of a feeler mounted to be engaged by a surface in the shuttle and pushed frontwardly thereby on a detecting beat, and constructed to bend laterally when an end thereof is held by filling on a detecting beat 95 and to yieldingly resist a laterally bending force, means for deflecting the intermediate portion of the feeler laterally as the feeler is pushed frontwardly on a detecting beat, filling engaging teeth for holding the rear 100 end of the feeler from moving longitudinally of the shuttle on a detecting beat until substantial exhaustion of filling occurs, and means for effecting replenishment of filling upon movement of the rear end of the feeler 105 longitudinally of the shuttle.
5. In a feeler mechanism for looms, the combination of a laterally bendable feeler mounted to be engaged by a surface in the shuttle and pushed frontwardly thereby on a 110 detecting beat, means for yieldingly resisting a force tending to bend the feeler, a pivoted link for deflecting an intermediate portion of the feeler laterally as the feeler is pushed frontwardly on a detecting beat, 115 teeth to engage the filling and hold the rear end of the feeler from moving longitudinally of the shuttle on a detecting beat until filling is substantially exhausted, and means operable by movement of the feeler longitudinally of the shuttle to effect replenishment of filling. 120
6. In a feeler mechanism for looms, the combination of a feeler mounted for movement longitudinally of the shuttle and to be pushed frontwardly on a detecting beat by a surface carried by the lay, means for moving an intermediate portion of the feeler laterally as the feeler is pushed 125 frontwardly on a detecting beat, teeth 130

upon the rear end of the feeler engageable with the filling to hold said rear end from moving longitudinally of the shuttle until substantial exhaustion of filling occurs, 5 said feeler constructed to bend laterally on a detecting beat when its rear end is held by the filling, and spring means tending to resist the bending of the feeler.

7. In a feeler mechanism for looms, the 10 combination of a leeler stand, a feeler mounted thereupon for movement longitudinally of the shuttle and to be pushed frontwardly on a detecting beat by a surface carried by the lay, a link pivotally connected to the stand and feeler, respectively, for moving a portion of the feeler laterally on each detecting beat as the feeler is pushed frontwardly, teeth upon the feeler engageable with the filling to hold the rear end of 20 the feeler from moving longitudinally of the shuttle until substantial exhaustion of filling occurs, said feeler constructed to bend laterally upon a detecting beat when its rear end is held by filling, yielding means for 25 restoring the feeler to its straightened position, and means operable by movement of the rear end of the feeler longitudinally of the shuttle to effect replenishment of filling.

8. In a feeler mechanism for looms, the 30 combination of a feeler bendable intermediate its ends and mounted for movement longitudinally of the shuttle and to be pushed frontwardly on a detecting beat by a surface carried by the lay, means for yieldingly resisting a force acting to bend the feeler, means for moving an intermediate portion of the feeler laterally on each detecting beat as the feeler is pushed frontwardly, filling engaging teeth for preventing the 40 rear end of the feeler from being moved longitudinally of the shuttle when the intermediate portion thereof is moved laterally until filling is substantially exhausted, and means operable by the movement of the 45 feeler longitudinally of the shuttle to effect replenishment of filling including an arm having an end adjacent the rear end of the feeler to be operated thereby.

9. In a feeler mechanism for looms, the 50 combination of a feeler which is jointed between its ends to permit the feeler to bend laterally, means acting upon the feeler as it is moved frontwardly on a detecting beat to bend the feeler when the rear end 55 of the feeler is held from movement longitudinally of the shuttle by a working supply of filling on a detecting beat and acting to move the rear end of the feeler longitudinally of the shuttle without bending it when 60 the filling is substantially exhausted on a detecting beat.

10. In a feeler mechanism for looms, the combination of a feeler jointed between its ends and mounted on the frame of the loom

to enter the shuttle as the lay beats up and 65 feels for the filling, yielding means normally acting to maintain the front and rear portions of the feeler in alinement, and means tending to break the joint of the feeler when a working supply of filling is 70 present in the shuttle on a detecting beat and to move the feeler longitudinally of the shuttle without breaking the joint when the filling is substantially exhausted on a detecting beat. 75

11. In a feeler mechanism for looms, a feeler mounted for movement toward and from the front of the loom and formed of jointed sections only one of which is adapted to engage a surface carried by the lay, means 80 normally acting to hold the sections in extended relation, and means acting to break the joint of the feeler as it is pushed frontwardly by the filling on a detecting beat and while its end is held by the filling from moving 85 longitudinally of the shuttle.

12. In a feeler mechanism for looms, the combination of a feeler stand, a jointed feeler mounted on the stand for movement toward and from the front of the loom, a 90 guide through which the front end portion of the feeler extends, and means acting upon the feeler between the guide and rear end of the feeler to break the joint of the feeler as it is moved frontwardly when the rear 95 end of the feeler is held from movement longitudinally of the shuttle by the filling on a detecting beat.

13. In a feeler mechanism for looms, the combination of a feeler stand, a jointed 100 feeler mounted on the stand for movement toward and from the front of the loom, a guide through which the front end portion of the feeler extends, a spring normally acting to maintain the front and rear portions 105 of the feeler in alinement, and means acting upon the feeler between the guide and rear end of the feeler to break the joint of the feeler as it is moved frontwardly when the rear end of the feeler is held from movement 110 longitudinally of the shuttle by the filling on a detecting beat.

14. In a feeler mechanism for looms, the combination of a feeler having a toothed filling engaging end and a joint between the 115 filling engaging and front end of the feeler, means including a spring normally acting upon the joint to maintain the joint closed, and means acting to break the joint of the feeler as the lay moves frontwardly when a working supply of filling is in the shuttle on a detecting beat and the rear end is held by the filling from movement longitudinally of the shuttle. 120

In testimony whereof, I have signed my 125 name to this specification.

ISAAC SNOW.
